LIQUID HEATER AND VAPORIZER

Fred H. Daniels, Worcester, Mass., assignor to
La Mont Corporation, New York, N. Y., a cor-
poration of New York

Application April 28, 1930, Serial No. 447,971

19 Claims. (Cl. 122—504)

This invention relates to liquid heaters and vaporizers, and more particularly to steam generating apparatus in which means is provided for creating a forced circulation of water through 5 the heat exposed elements.

A steam generator of the type shown in the United States patent to La Mont Reissue No. 16,895 comprises a pump which draws water from a drum or other container and forces it into 10 generating tubes exposed to the heat of a furnace. In such an apparatus an adequate supply of water to the tubes is essential in order to prevent the tubes from reaching a dangerously high temperature. This has been recognized, and it has heretofore been proposed to 15 utilize an auxiliary pump which will be placed in operation automatically upon failure of the main pump to maintain the desired rate of flow. However, such an auxiliary pump with its driving means represents a considerable investment, and even if used there is always a possibility that 20 it will become inoperative at a time when it is most needed. Similar problems arise in other types of liquid heating apparatus.

It is accordingly the main object of my invention to provide a simple and inexpensive construction which will serve to insure an adequate flow of liquid through the heat exposed elements 25 of a liquid heater whenever a condition occurs which tends to reduce the flow to the danger point, such as, for example, failure of the usual flow producing means to function properly.

It is a further object of my invention to provide a steam generating apparatus having heat 30 exposed generating elements through which water is forced by means of a pump, and which is so arranged that even though the pump or its driving means should fail a sufficient quantity of water will nevertheless be positively forced 35 into the generating elements to prevent them from burning out.

With these and other objects in view, as will be apparent to those skilled in the art, my invention resides in the combination of parts set 40 forth in the specification and covered by the claims appended hereto.

In accordance with my invention, I provide a liquid heating apparatus having heat exposed elements to which liquid is delivered by a suitable 45 means such as a pump. In order to protect the apparatus against overheating in the event that the flow for any reason falls below the amount required for protection, I provide safety mechanism actuated in accordance with the flow con- 50 ditions which is effective to alter the pressure

conditions in the system and to cause liquid to flow to the elements from a source of liquid and so protect them from overheating. In the preferred embodiment of my invention I utilize a mechanism which upon reduction of the flow 60 to a predetermined amount serves to reduce the pressure at the discharge ends of the heating elements and thus permits liquid to flow through the elements from a supply at their inlet ends. This supply is preferably at such a pressure as 65 will produce the desired flow.

Referring to the drawing illustrating one embodiment of my invention and in which like reference numerals indicate like parts:

Fig. 1 is a vertical sectional elevation of a 70 steam generating apparatus; and

Fig. 2 is an enlarged detail in section showing a portion of the inlet header and one of the generating tubes.

The drawing illustrates an embodiment of the 75 invention arranged for steam generation. It will be clear, however, from the following description that the invention may be used in connection with various other types of heat exchange apparatus. The embodiment illustrated comprises a furnace chamber 10 which is maintained 80 at a high temperature by any suitable means. For this purpose I have shown an oil burner 11 arranged to deliver oil for combustion in the furnace in a well known manner.

A boiler 12 of any desired type is mounted 85 above the furnace to absorb heat therefrom by radiation and convection. For simplicity of illustration, this boiler 12 has been shown as a horizontal cylindrical drum forming a receptacle for 90 water and steam under pressure. Water may be supplied to the drum 12 from any suitable source through a feed pipe 14, and steam may be withdrawn from the drum through a pipe 15 leading to a main steam header 16.

Adjacent to one wall of the furnace chamber 10 I have shown a water wall comprising spaced 95 parallel horizontal tubes 18 arranged to generate steam by the absorption of radiant heat from the furnace and to protect the refractory material of the wall behind them. The tubes 18 are connected at one end to a vertical pipe or inlet header 19, and at their opposite ends to a vertical outlet header 20. A suitable forcing means, such as a centrifugal pump 22 driven by an electric motor 23, is provided to circulate water 100 through the tubes. A pipe 24 is connected to the drum 12 below the water line and leads to the inlet of the pump 22. The discharge of the pump 105 is connected to the inlet header 19 of the water 110

wall. The outlet header 20 is connected by a pipe 26 with the steam space of the drum 12.

With this construction the pump 22 draws water from the drum 12 through pipe 24 and delivers it under pressure to inlet header 19 and tubes 18. The steam which is formed in the tubes, together with any unevaporated water, passes back to the drum 12 through header 20 and pipe 26. The entrance end of each tube 18 is preferably restricted by means of an orifice plate 27 (Fig. 2) for the purpose of properly distributing the water among the tubes.

The present invention as applied to the construction so far described is primarily concerned with an arrangement for continuing the supply of water to tubes 18 in the event pump 22 should fail to function properly. The invention is thus in the nature of a safety device to protect the tubes from overheating under these circumstances.

In order to accomplish my purpose, I provide means automatically actuated upon failure of pump 22 which serves to close off the outlet header 20 from drum 12 and also to relieve the pressure in this header, for example by permitting the header to discharge to a lower pressure and preferably to the atmosphere. The pressure in drum 12 is then effective to force water through the tubes 18 connected thereto.

In the specific embodiment illustrated I have shown an emergency discharge or exhaust pipe 28 leading from pipe 26 to atmosphere or to any suitable point for discharge of water and steam at a lower pressure than that of the boiler 12, such as the blow down system for example. A valve 30 in pipe 29 normally prevents flow therethrough. An orifice plate 31 may also be provided in pipe 29 to limit the rate of flow, in case valve 30 is open, to an amount slightly in excess of that necessary to protect the tubes 18. A check valve 32 located in pipe 28 between pipe 29 and the boiler prevents the discharge of steam from the boiler through pipe 29 when valve 30 is open. This check valve may be of the ordinary swing type having a valve member 33 pivoted to the body portion of the valve and arranged to be held open by the normal flow in pipe 26 in the direction of the drum and to close tightly against its seat whenever the flow tends to reverse its direction.

Various constructions may be utilized within the scope of my invention to open valve 30 automatically in the event pump 22 should fail to maintain the desired rate of flow. The preferred arrangement illustrated has been fully disclosed in the prior application of Charles M. Terry, Serial No. 445,978, and comprises a flexible diaphragm 34 connected directly to valve 30 by a rod 35. The diaphragm is subjected to the fluid pressure in a diaphragm chamber 37, and this pressure is opposed by a compression spring 38 and by the boiler pressure which is normally effective beneath the valve. It will thus be seen that the spring 38 serves to bias the valve 30 toward open position, and the valve will remain closed only so long as the pressure in chamber 37 exceeds a predetermined amount.

The preferred construction for controlling the fluid pressure in chamber 37 comprises a casing 40 shaped to form a chamber 41 which is connected to chamber 37 by means of a pipe 42. A pipe 44 leads from inlet header 19 to chamber 41, and the fluid pressure in the inlet header is thus normally effective in chamber 37 to hold valve 30 closed. Chamber 41 is provided with an outlet passage leading to a discharge pipe 46, which may be connected to a drain, and the flow through the

outlet passage is controlled by a valve 47 which is normally held closed so long as the proper flow is being maintained through the generating tubes 18 by pump 22.

In order to obtain the desired automatic operation I provide a flexible diaphragm 48 connected by a rod 50 to the valve 47 and preferably subjected to a fluid pressure differential which is a function of the rate of flow in the tubes 18. Such a pressure differential exists as a result of the orifice plate 27 at the entrance of each generating tube, and may be utilized by connecting a pipe 51 to one of the tubes 18, as shown in detail in Fig. 2, and leading this pipe to a chamber 53 beneath the diaphragm 48. The pressure in chamber 41 is made effective above the diaphragm, so that the pressure differential between the header 19 and tubes 18 tends to hold valve 47 closed. A compression spring 54 beneath the diaphragm 48 serves to oppose this pressure differential and to bias the valve 47 toward open position. The valve will therefore open whenever the rate of flow and the resulting pressure drop falls below a predetermined value. An orifice plate 56 is preferably provided in pipe 44 to restrict the flow into chamber 41 when valve 47 is open, and thus prevent the building up of pressure in the chamber under these conditions. A valve 57, normally operable by means of a hand lever 58, is preferably located in the outlet from chamber 41 in series with valve 47, in order that pressure may be built up in chamber 41 to close valve 30 after pump 22 has been restored to operation. Valve 57 may be biased toward open position by a compression spring 60.

The operation of the invention will be apparent from the above disclosure. Under normal conditions water will be withdrawn from the boiler 12 by pump 22 through pipe 24 and delivered to inlet header 19 under pressure. This water will flow through the orifices at the entrance to the tubes 18 and the steam and excess water will be returned to the boiler through header 20, pipe 26, and check valve 33. The pressure differential on opposite sides of the orifice plate 27 will be effective on diaphragm 48, and the valve 47 will thus be held closed. The pressure in inlet header 19 will therefore be effective on diaphragm 34 to hold valve 30 closed. Valve 57 is held open by spring 60. If now the flow of water from the pump 22 should stop for any reason, such as a failure of the electric supply to the motor 23, the flow into the tubes 18 and the resulting pressure differential effective upon diaphragm 48 will decrease. Under these conditions spring 54 will open valve 47 and permit fluid to flow out of pipe 46, thus relieving the pressure in chamber 41, pipe 42 and chamber 34, and permitting spring 38 to open the valve 30. This will cause steam to flow out through the exit pipe 29 and relieve the pressure in the tubes 18. Check valve 32 will close to prevent escape of steam from the boiler 12, and the steam pressure in the boiler will now force water through pipe 24, pump 22, header 19, tubes 18, header 20, pipe 26, and pipe 29 at a rate sufficient to protect the tubes 18 from burning out. In the meantime the operator can shut down the oil burner 11 and correct the difficulty which caused failure of pump 22. With valve 47 open, orifice plate 56 limits the flow through pipe 46 to a slight amount and prevents the building up of pressure in chamber 41. After pump 22 has been placed in operation once more, the operator can close valve 57 by hand. Pressure will then build up in chamber 100

41 until it equals the inlet header pressure, valves 30 and 47 will close, and valve 57 may then be opened without relieving the pressure in chamber 41.

5 It will be seen that the present invention provides a reliable and effective protection for steam generating apparatus and other types of liquid heaters in which an adequate flow of liquid is essential for their continued operation. The construction is simple and inexpensive to manufacture, and does not require auxiliary pumps or driving means.

Having thus described my invention, what I claim as new and desire to secure by Letters Patent is:

15 1. A liquid heating apparatus comprising elements carrying fluid under pressure which are arranged to be exposed to heat, a discharge connection therefrom, means connected to said elements and providing a supply of liquid under pressure, a pump arranged normally to deliver to said elements the liquid to be heated, and means for confining and controlling the fluid carried by said elements and arranged to be actuated upon failure of said pump to exhaust fluid from said discharge connection and thereby to reduce the pressure therein sufficiently to cause said liquid supply pressure to deliver liquid to the elements.

20 2. A liquid heating apparatus comprising elements arranged to be exposed to heat and to carry fluid under pressure, a discharge connection therefrom, a receptacle connected to said elements and providing a supply of liquid under pressure, a pump to deliver to said elements the liquid to be heated, and fluid control means arranged to be actuated so as automatically to exhaust fluid from said discharge connection whenever the rate at which liquid is delivered to the elements by the pump falls below a predetermined amount and thereby to reduce the pressure therein sufficiently to cause said liquid supply pressure to deliver liquid to the element.

25 3. A liquid heating apparatus comprising a receptacle containing liquid under pressure, elements arranged to be exposed to heat and to carry fluid under pressure, means to deliver liquid from the receptacle to the elements, an exhaust pipe connected to said elements, a valve in said pipe which is normally closed, and means actuated by a force caused by the flow of the liquid to the elements and acting when the rate of flow of liquid to the elements falls below a predetermined amount to open the valve and lower the pressure in the exhaust pipe sufficiently to cause the pressure in said receptacle to force said liquid from the receptacle into said elements whereby to restore the flow of liquid from the receptacle into the elements.

30 4. A liquid heating apparatus comprising a receptacle containing liquid under pressure, elements arranged to be exposed to heat and to carry fluid under pressure, means to deliver liquid from the receptacle to the elements, an exhaust pipe connected to said elements, a valve in said pipe which is normally closed, and a device actuated by a pressure caused by the flow of the liquid to said elements and controlled in relation to the rate of flow of liquid to the elements which, upon said rate lowering below a predetermined amount, will operate to open the valve and lower the pressure in the elements sufficiently to cause the pressure in the receptacle to force the liquid therein into said elements and thereby restore the flow of liquid thereto from the receptacle.

75

5. A liquid heating apparatus comprising liquid heating elements arranged to be exposed to heat, means connected to said elements and providing a reservoir of liquid under pressure, means to supply liquid under pressure to said elements, means providing a discharge outlet from the elements, and means responsive to variations in a force caused by the flow of liquid to the elements which is effective to open the discharge whenever the rate of flow falls below a predetermined amount and thereby to reduce the pressure therein sufficiently to cause a flow of liquid from said reservoir through said elements in amount sufficient to protect the elements.

80 6. Vapor generating apparatus comprising a receptacle containing liquid under pressure, a plurality of tubes arranged to be exposed to heat, a pump to deliver liquid from said receptacle to said tubes, a connecting pipe through which vapor and any unevaporated liquid from the tubes is normally conveyed back to the receptacle, and fluid control means associated with said connecting pipe and automatically actuated upon failure of the pump to deliver liquid to the tubes at a rate in excess of a predetermined amount and arranged to cause the vapor and any unevaporated liquid from the tubes to be discharged to a pressure less than that in the receptacle, whereby the pressure in the receptacle will force liquid into the tubes.

85 7. Steam generating apparatus comprising a drum containing water under pressure, a plurality of tubes arranged to be exposed to the heat of a furnace, a pump to deliver water from the drum to the tubes for evaporation therein, a steam discharge connection for the tubes normally carrying the steam at a pressure substantially equal to that in the drum, and fluid pressure reducing means connected and arranged to reduce the pressure in the discharge connection automatically upon failure of the pump to supply water to the tubes at a rate in excess of a predetermined amount and sufficiently to cause the pressure in the drum to force water into the tubes.

90 8. Steam generating apparatus comprising a boiler, a furnace arranged to supply heat to the boiler and generate steam under pressure therein, a plurality of tubes forming a water wall exposed to the radiant heat of the furnace, a pump arranged to withdraw water from the boiler and deliver it to the tubes, a connection between the discharge ends of the tubes and the boiler through which steam and any unevaporated water from the water wall tubes are normally returned to the boiler, and valvular means associated with said connection and arranged to be effective, upon failure of the pump to deliver water to the tubes at a rate in excess of a predetermined amount, to cause discharge of the steam and any unevaporated water from the water wall tubes to the atmosphere instead of to the boiler and concomitantly to cause the steam pressure in the boiler to force water into the tubes.

95 10 9. Steam generating apparatus comprising a boiler, a furnace arranged to supply heat to the boiler and generate steam under pressure therein, a plurality of tubes forming a water wall exposed to the radiant heat of the furnace, a pump arranged to withdraw water from the boiler and deliver it to the tubes, an orifice plate at the entrance of each tube restricting the flow thereto, a connecting pipe to convey steam and any unevaporated water from the water wall tubes back to the boiler, a branch pipe leading from the connecting pipe to the atmosphere and having a valve there-

in, means to open the valve automatically whenever the rate of flow into the tubes falls below a predetermined amount, thereby causing the steam pressure in the boiler to force water into the tubes and protect them from burning, and a check valve in the connecting pipe between the branch pipe and the boiler to prevent the escape of steam from the boiler when the valve is open.

10. A heat exchanger having heat exchanging surfaces, means normally effective to cause a liquid to flow in heat exchanging contact with said heating surfaces to produce a heated fluid, means providing a reservoir supply of liquid under pressure connected to the heat exchanging surfaces so as to supply liquid thereto, fluid control means constructed and arranged to be effective upon a predetermined change in the operation of the means normally causing flow of the liquid in said heat exchanging contact to cause 15 the pressure of said liquid in said reservoir to deliver the liquid to said heat exchanging surfaces and cause it to flow in heat exchanging contact therewith.

11. A steam generating apparatus comprising a steam generating tube, means normally effective to deliver water to one end of said tube in quantity in excess of the evaporation therein, means at said end of said tube for limiting the quantity of water delivered to the tube to an amount insufficient to fill the cross sectional area of the tube so as to leave space within the tube for the steam, said limitation normally creating a pressure differential in the water flow, a discharge connection from said tube, means providing a storage volume of water under pressure connected to said water inlet end of the tube, and fluid control means constructed and arranged to be operated by said differential pressure and to be effective upon a predetermined 40 change in said differential pressure to reduce the pressure in said discharge connection sufficiently to cause water from said storage volume to be delivered through said water limiting means to maintain the flow of water through the tubes 45 in excess of the steam generated therein.

12. Heat exchange apparatus comprising a liquid heating element exposed to heat, means normally providing flow of liquid to said element, means connected to said element for withdrawing heated fluid therefrom during normal flow of liquid thereto, fluid control means also connected to said element normally preventing flow through itself of the heated fluid but arranged when actuated to cause flow therethrough of said fluid, means acted upon by a force derived from the flow of the liquid to said element and arranged to actuate said fluid control means when the delivery of the liquid to the element corresponding to normal withdrawal of the heated fluid is reduced below a predetermined amount, and a supply of liquid under pressure connected to said element and so arranged in connection with said fluid control means as to cause flow of liquid to said element from said supply to tend to restore said normal flow upon actuation of said fluid control means.

13. Heat exchanger comprising means providing a supply of liquid under pressure, a heat exchanging surface, liquid delivery means connected and arranged to withdraw liquid from said liquid supply and deliver it to said heat exchanging surface to produce by heat exchanging contact with said surface a heated fluid, means for so confining said heated fluid as to maintain it 75 at a pressure normally not less than the pressure

of said liquid supply, fluid pressure control means actuated in accordance with variations in a force derived from the delivery of the liquid to said heat exchanging surface and arranged to reduce the pressure of said heated fluid when said liquid delivery is reduced below a predetermined amount, the arrangement of said liquid supply and said heat exchanging surface and said fluid pressure control means being such as to cause the pressure of said liquid supply to deliver liquid to said heat exchanging surface and to discharge the heated fluid therefrom to said reduced pressure upon actuation of said fluid pressure control means when said liquid delivery is reduced below said predetermined amount.

14. Heat exchange apparatus comprising a receptacle containing liquid under pressure, a tube exposed to heat, means connected to deliver liquid to the tube and to cause said liquid to flow through said tube to produce a heated fluid under pressure, and fluid pressure reducing means actuated in accordance with a predetermined variation in the rate of delivery of the liquid to the tube and arranged to reduce the pressure of said heated fluid upon reduction of said rate of delivery below a predetermined amount, said receptacle and said fluid pressure reducing means being so connected to said tube that upon reduction of the pressure of the heated fluid the pressure in the receptacle is effective to deliver liquid therefrom to the tube for flow therethrough to produce the heated fluid.

15. Steam generating apparatus comprising a drum containing water subjected to the pressure of the generated steam, a plurality of tubes exposed to steam generating heat, a pump to deliver from the drum to the tubes at one end thereof the water to be evaporated into steam therein, a steam collector connected to the other ends of the tubes to collect steam from said tubes and to deliver it to the steam space of the drum and arranged so as normally to have a pressure therein not less than the pressure of the steam in the drum, fluid pressure reducing means connected to said collector and arranged to be actuated automatically, upon failure of the pump to supply water to the tubes at a rate in excess of a predetermined amount, to reduce the pressure in said collector below the pressure of the steam in said drum, and fluid flow control means arranged to cause said steam pressure to force water from the drum into tubes for flow therethrough toward said collector while preventing reverse flow of steam from said drum to said collector.

16. A fluid heating apparatus comprising an element arranged to be exposed to heat, means for normally delivering to said element the fluid to be heated, means so connected to said element and providing a volume of fluid in such condition of pressure that fluid is capable of flowing from said volume of fluid to said element in like manner to said normal flow, a discharge connection from said element, means responsive to variations in a force derived from a predetermined change in the normal flow of fluid to the element and arranged to reduce the pressure in said discharge connection relative to that of the volume of fluid sufficiently to cause flow of fluid from said volume of fluid to said element upon said change in the normal flow.

17. A fluid heating apparatus comprising an element arranged to be exposed to heat, means for normally delivering to said element the fluid to be heated, means providing a volume of fluid

under pressure so connected to said element that under said pressure fluid may flow from said volume of fluid to said element in like manner to said normal flow, a discharge connection from 5 said element, means including fluid control means and responsive to variations in a force derived from the flow of fluid to the element and arranged to create a difference in pressure between the pressure of said volume of fluid and the pressure 10 within said discharge connection such as will cause flow of fluid from said volume of fluid to said element upon a predetermined change in the normal flow of fluid to the element.

18. A liquid heating apparatus comprising elements arranged to be exposed to heat, a discharge connection therefrom, means connected to said elements and providing a reservoir supply 15 of liquid under pressure, means normally effective to deliver to said elements the liquid to be heated therein to produce the heated fluid, and fluid control means automatically responsive to

failure of said delivery means to cause said reservoir supply means to be connected through said elements and said discharge connection to a reduced pressure sufficiently below that of the liquid in said reservoir to maintain a constant supply of said liquid through said elements. 80

19. A liquid heating apparatus comprising elements arranged to be exposed to heat, means connected to said elements and providing a volume of liquid, means to supply liquid to said elements, a discharge connection from said elements, and means responsive to variations in a force derived from the flow of the liquid to said elements including fluid control means arranged to relieve the pressure from the discharge connection whenever the rate of flow of said liquid decreases below a predetermined amount and thereby to reduce the pressure therein sufficiently to cause a flow of liquid from said volume through said elements sufficient to protect the elements. 90 95
